UNITED STATES PATENT OFFICE.

JOHN D. BANKS, OF COLWYN, PENNSYLVANIA, ASSIGNOR TO VICTORY MANUFACTURING CO., OF AUDUBON, NEW JERSEY.

DESIGN FOR A GLARE-SHIELD FOR VEHICLES.

58,696.

Specification for Design.

Patented Aug. 30, 1921.

Application filed April 28, 1921. Serial No. 465,234. Term of patent 14 years.

To all whom it may concern:

Be it known that I, JOHN D. BANKS, a citizen of the United States, residing at Colwyn, in the county of Delaware and State of Pennsylvania, have invented a new, original, and ornamental Design for a Glare-Shield for Vehicles, of which the following is a specification, reference being had to the accompanying drawing, forming a part thereof, in which—

Figure 1 is a face view of a glare shield, showing my new design,

Fig. 2 is a top plan view of Fig. 1,
Fig. 3 is an end elevation of Fig. 1, and
Fig. 4 is a view showing the reverse side
of Fig. 1.

I claim:

The ornamental design for a glare shield
for vehicles, as shown.

JOHN D. BANKS.
